UNITED STATES PATENT OFFICE

159,109

SHUFFLEBOARD GAME TABLE

Harold V. Storey, Seattle, Wash.

Application February 1, 1949, Serial No. 597

Term of patent 7 years

(Cl. D34—5)

To all whom it may concern:

Be it known that Harold V. Storey, a citizen of the United States, residing at Seattle, King County, Washington, has invented a new, original, and ornamental Design for a Shuffle Board Game Table, of which the following is a specification, reference being had to the accompanying drawing, forming a part thereof, in which

Figure 1 is a perspective view of a shuffle board game table, showing my new design;

Figure 2 is a cross sectional view thereof taken along lines 2—2 in Figure 1; and

Figure 3 is a cross sectional view thereof taken along lines 3—3 of Figure 1.

I claim:

The ornamental design for a shuffle board game table, as shown.

HAROLD V. STOREY.
